UNITED STATES PATENT OFFICE

171,426

BOOK END OR SIMILAR ARTICLE

Mynna Fox Shulman, Baltimore, Md.

Application December 19, 1951, Serial No. 17,779

Term of patent 14 years

(Cl. D33—1)

To all whom it may concern:

Be it known that I, Mynna Fox Shulman, a citizen of the United States, residing at 6715 Park Heights Avenue, Baltimore city, State of Maryland, have invented a new, original, and ornamental Design for a Book End or Similar Article, of which the following is a specification, reference being had to the accompanying drawing, forming a part hereof.

Fig. 1 is a side elevational view of a book end or similar article, showing my new design;

Fig. 2 is a front elevational view thereof; and

Fig. 3 is a side elevational view thereof showing the side opposite to the one shown in Fig. 1.

I claim:

The ornamental design for a book end or similar article, as shown.

MYNNA FOX SHULMAN.
